UNITED STATES PATENT OFFICE

LEWIS J. BAZZONI, OF SWAMPSIDE, MASSACHUSETTS, ASSIGNOR TO UNITED SHOE MACHINERY CORPORATION, OF PATERSON, NEW JERSEY, A CORPORATION OF NEW JERSEY

COVERED HEEL AND METHOD OF MAKING SAME

Application filed January 26, 1929. Serial No. 335,361.

This invention relates to improvements in covered heels and to improvements in the art of heel covering.

In United States Letters Patent No. 1,691,149, granted Nov. 13, 1928, upon application of Anthony Cocozella, there is disclosed a covered heel in which a paneled effect is obtained at the heel breast by countersinking a breast-covering flap within a recess 10 formed in the breast face.

One object of the present invention is to reduce the expense of making covered heels having paneled breast surfaces.

With this object in view, and in accordance 15 with the present invention, a paneled effect has been obtained in a covered heel without recessing or otherwise specially preparing the surface of the heel in order to facilitate the production of the desired effect, and a heel 20 has been provided with a breast covering comprising frame and panel members having respectively portions overlapped upon the breast face of the heel and constructed and arranged to provide substantially flush joints 25 between said members. As shown, the extent of overlap of the frame and panel members is such as to insure against danger of any portion of the heel core becoming exposed to view as a result of shrinkage of the heel covering. 30 As illustrated, the paneled effect has been produced at the breast of a Cuban heel and to this end a covering for the rear and sides of the heel has been provided with extensions arranged to overlap the lateral margins of the 35 heel breast, and a separate breast cover or flap has been applied so as partially to overlap the side cover extensions, the lateral edges of the separate breast cover being spaced inwardly from the breast corners of the heel so as to leave exposed upon the breast surface at each side of the breast cover relatively narrow portions of the side cover extensions in order that these narrow portions may serve to 40 frame the separate breast cover and thereby produce the desired paneled effect. As herein shown, the edge thickness of the panel member may, if necessary, be reduced by beveling or skiving to such an extent that substantially flush joints are formed between the

panel and the frame members, thus improving the appearance of the heel.

As illustrated, the side cover extensions or frame portions are rabbeted to receive the overlapping margins of the breast covering 55 or panel, a shoulder being formed along the inner edge of each rabbeted portion to be engaged by the respective lateral edge of the breast covering so that, while the joints formed between the panel and frame portions 60 of the breast covering have the outward appearance of ordinary butted joints, nevertheless, on account of the overlapping margins between the shoulders on the frame portions, the surface of the heel core can not become 65 exposed even though the cover joints should open up more or less because of shrinkage of the covering or for any other reason. Moreover, as illustrated, the rabbeting is accomplished in such a way as to provide a 70 beveled surface extending from each shoulder to the outer extremity of each side cover extension to receive the overlapping margins of the breast covering without producing undesirable ridges in the latter. This construction and arrangement is further advantageous 75 inasmuch as it insures against the presence of any disfiguring bulge or ridge where the side cover extensions are overlapped by the breast covering and insures that a 80 flush joint will be secured between these portions of the heel covering.

The invention also provides an improved method of covering heels which, as herein illustrated, consists in applying to one face 85 of a heel a cover portion adapted to constitute a panel and another cover portion in position to frame one side of the panel, one of said cover portions having a beveled margin and the other having an unbeveled margin, and securing said margins together with 90 said unbeveled margin superposed upon said beveled margin.

Other features of the invention will be apparent from the following description and will be particularly defined in the appended claims.

In the drawings,

Fig. 1 is a perspective view of a covered heel embodying features of the present invention.

tion whereby a panel effect is obtained at the heel breast;

Fig. 2 is a sectional view on an enlarged scale taken along the line II—II of Fig. 1;

5 Figs. 3 to 7, inclusive, are fragmentary sectional views illustrating successive steps in the improved method of heel covering hereinafter described;

10 Fig. 8 is a fragmentary sectional view of a covered heel illustrating a further step which may be performed in the practice of this method; and

15 Fig. 9 is a fragmentary sectional view showing a modification of the construction illustrated in Figs. 1 and 2.

20 Referring to Figs. 1 and 2, the invention is illustrated as embodied in a heel H having a side cover C and a breast covering B. The side cover C extends around the rear and 25 sides of the heel in the customary manner and has end portions or extensions E which are turned inwardly at the breast corners to overlap the lateral margins of the heel breast. The breast covering B is of less width than 30 the heel breast and is applied so that while its lateral margins overlap the side cover extensions E they do not entirely cover these extensions but leave narrow portions thereof exposed to view at each side of the breast covering so that a paneled heel breast effect is produced, the breast covering B constituting the panel and the side cover extensions E serving to frame the opposite sides of the panel. In 35 order to form flush joints between the breast covering B and the side cover extensions E the latter are shown as being rabbeted to provide depressed surfaces D for engagement with the margins of the breast covering and shoulders S against which the edges of the 40 breast covering abut. To avoid the presence of undesirable ridges or bulges where the breast covering overlies the inner extremities of the side cover extensions, the depressed surfaces D are beveled to form feathered inner edges so that when the side cover extensions are laid in place against the breast edges of the heel the depressed surfaces D will 45 blend with the transverse curvature of the breast face. The shoulders S are formed by 50 cuts which, as shown in Fig. 1, are parallel to the adjacent breast edges or corners of the heel. The breast cover B is trimmed to fit 55 exactly within the space between the shoulders S at the opposite sides of the heel breast and preferably the depth of the shoulder cuts is the same as the thickness of the breast cover so that the outer surface of the breast cover is flush with the exposed surfaces of 60 the side cover extensions.

65 In applying the side cover C it is coated with adhesive and wrapped around the rear and sides of the heel in the usual way, the opposite end portions or extensions E of the cover being left projecting beyond the breast corners, as shown in Fig. 3.

The rabbeting of each side cover extension may be effected, as shown in Fig. 4, by the single stroke of a skiving knife such as a hand knife 12 having a single flat blade. To produce this result, as shown, the side cover extension is supported upon the beveled surface 14 at one end of a plate 16 which is laid against the uncovered breast surface of the heel. The knife, while being drawn across the side cover extension, is guided by the un-beveled upper surface of the plate 16 which is engaged by the free extremity of the knife blade. The angle between the beveled surface 14 and the unbeveled upper surface of the plate 16 is such that when the side cover extension is bent sharply over the end of the plate and made to assume the position shown in Fig. 4 the path of the knife, as determined by the plane of the unbeveled upper surface of the plate 16 is such as to cut 70 through the outer surface of the cover extension along a line X located between the bend and the heel so that after the cut has been made the thickness of the bent-over portion of the cover extension, at its junction with the unbent portion thereof, is substantially less than the full thickness of the cover. Accordingly, when the bend is subsequently removed from the cover extension by laying it against the heel breast, as shown in Fig. 5, the innermost portion of the skived surface will be disposed at an abrupt angle to the remainder of the skived surface, thereby forming the shoulder S. The thickness of the plate 16 serves to space the shoulder S 75 from the corner of the heel breast and to insure that it will be parallel to the adjacent lateral edge of the heel breast. The distance between the shoulder S and the lateral edge of the heel breast may be varied by using 80 plates 16 of different thicknesses. Furthermore, by employing plates having their end portions beveled at different angles, corresponding variations may be secured in the angle of bevel which is to be imparted to the 85 side cover extensions. When the side cover extensions have been laid against the margins of the heel breast as above described they are firmly secured to the breast by the 90 adhesive previously applied to the cover. 95

The breast coverings B are initially cut wide enough to overlap the unrabbeted portions of the side cover extensions and after being coated with adhesive and applied to the heel breast they appear as shown in Fig. 6. Subsequently the opposite lateral margins of the breast covering B are trimmed to adapt 100 the covering to fit within the space between shoulders S, the paths of the trimming cuts being gaged from the adjacent lateral edges 105 of the heel. For this purpose a hand trimming tool such as that shown at 18 in Fig. 8 may conveniently be employed. As shown this tool comprises a rotary trimming knife 110 formed at one side of a gage roll 22 adapt- 115

ed to engage the outer edge of the breast covering to limit the depth of cut made by the knife 20 so that the knife will cut through the breast covering without injuring the underlying side cover extensions. As shown, also, an annular gage shoulder 24 is formed at the end of the roll 22 remote from the knife 20 for determining the path of trimming cut by engagement with the adjacent lateral edge or corner of the heel breast. By running this hand tool 18 along the breast corner from the top to the bottom of the heel the breast covering may be trimmed along lines coinciding with the lines of the shoulder cuts S. After being trimmed it is only necessary to press the lateral margins of the breast covering against the depressed surfaces D of the side cover extensions whereupon they will be securely held in place by adhesive previously applied to the breast covering.

If a breast covering is employed, having a thickness which is greater than the depth of the shoulders S, so that the margins of the breast covering project outwardly beyond the surfaces of the side cover extensions, this excess thickness may be reduced by the use of a buffering wheel such as that indicated at 26 in Fig. 8 thereby providing a flush joint between the breast covering and the side cover extensions.

In order to produce a paneled effect at the heel breast it is not essential, however, that the margins of the side cover extensions should be rabbeted as above described, inasmuch as a paneled effect may be obtained by providing a breast covering which is narrower than the full width of the heel breast and applying the covering so that its lateral margins overlap the side cover extensions but do not entirely cover them.

Preferably, as shown in Fig. 9, the margins of the breast covering and side cover extensions are initially beveled or feather edged by means of skiving or buffering operations to insure that substantially flush joints will be produced.

While the invention is herein illustrated and described in connection with its application to Cuban heels it is applicable also to Louis heels and the breast covering may be applied either before or after the heel is attached to a shoe. Moreover the breast covering may be an integral part of the shoe, e. g. a flap split from the sole and laid against the heel breast after the heel has been attached. Accordingly, the claims are not to be construed as limited to unattached heels but as covering also heels which are attached to shoes and the breasts of which are covered by means such as a flap which is integral with the sole of the shoe.

Having described my invention, what I claim as new and desire to secure by Letters Patent of the United States is:

1. A heel provided with a breast covering comprising frame and panel members having respectively portions overlapped upon the breast face of the heel and constructed and arranged to provide substantially flush joints between said members. 70

2. A heel having a paneled covering comprising frame portions having beveled margins, and a panel portion located between said frame portions and overlapping the 75 beveled margins only of the latter.

3. A heel having a paneled covering comprising frame portions having their inner margins rabbeted to provide shoulders spaced from the edges of said margins, and 80 a panel portion located between said frame portions and arranged with its opposite edges abutting the respective shoulders of said frame portions.

4. A heel having a paneled covering comprising a cover portion adapted to constitute a panel and another cover portion adapted to frame one side of the panel, one of said cover portions having a beveled margin and the other cover portion overlapping only the 90 beveled margins of said cover portion. 85

5. A heel having a paneled breast covering comprising frame portions overlying the lateral margins of the heel breast, and a panel portion partially overlapping said 95 frame portions and having its exposed surface flush with the exposed surfaces of said frame portions.

6. A heel having a paneled breast covering comprising side cover extensions overlapping the lateral margins of the heel breast, said extensions being beveled and the outer edges of the beveled surfaces of said extensions being spaced from the heel breast corners, and a breast cover having its lateral 100 margins overlapping the beveled surfaces of 105 the side cover extensions.

7. A heel having a paneled breast covering comprising side cover extensions overlapping the lateral margins of the heel breast, said extensions being beveled and the outer edges of the beveled surfaces of said extensions being spaced from the heel breast corners, and a breast cover having its lateral 110 margins overlapping the beveled surfaces of the side cover extensions and reduced in 115 thickness to provide flush joints between the breast cover and the side cover extensions.

8. A heel having a paneled breast covering comprising side cover extensions overlapping the lateral margins of the heel breast, said extensions having their outer surfaces rabbeted to provide shoulders spaced from the heel breast corners and margins of less thickness than the unrabbeted portions of the side cover extensions, and a breast cover having its lateral margins seated in the rabbeted portions of the side 120 cover extensions. 125

9. A heel having a paneled breast covering 130

- comprising side cover extensions overlapping the lateral margins of the heel breast, said extensions having their outer surfaces rabbeted to provide shoulders spaced from the heel breast corners and margins of less thickness than the unrabbeted portions of the side cover extensions, and a breast cover having its lateral margins of a thickness corresponding to the width of said shoulders seated in the rabbeted portions of the side cover extensions, the thickness of said lateral margins corresponding to the width of said shoulders so that the exposed surface of said cover is flush with the exposed surfaces of the side cover extensions. 10
10. A heel having a paneled breast covering comprising side cover extensions overlapping the lateral margins of the heel breast, each of said extensions having a shoulder formed in its exposed surface and spaced from the adjacent breast corner of the heel and having also a beveled surface extending from said shoulder to the inner edge of the extension, and a breast cover having its lateral margins overlying the beveled surfaces of the respective side cover extensions and its lateral edges abutting the shoulders of the respective side cover extensions. 20
20. That improvement in methods of covering heels which consists in rabbeting the margin of a heel covering, applying the rabbeted portion of said covering to one face of a heel to constitute a frame for a panel, applying a second covering to another face of the heel, and securing said coverings together with the margin of said second covering superposed upon said rabbeted margin. 30
30. That improvement in methods of covering heels which consists in rabbeting the margin of a cover portion and applying said cover portion to one face of a heel to frame one side of a panel, applying to said heel face a second cover portion adapted to constitute a panel and positioning it with its margin overlying the rabbeted margin of the first cover portion, trimming the margin of the second cover portion along the line of the inner edge of the channel formed by rabbeting the first cover portion, and fitting the 40 margin of the second cover portion within said channel. 40
40. That improvement in methods of covering heels which consists in assembling with a heel a cover portion adapted to constitute a panel and another cover portion adapted to frame one side of the panel, one of said cover portions having one of its margins rabbeted to provide a shoulder spaced from the edge of said margin and the other of said 50 cover portions having its margins unrabbeted, arranging said cover portions with an unrabbeted margin of one overlying the rabbeted margin of the other and overlapping the shoulder of said rabbeted portion, trimming said overlapping margin along the line 50
- 50 of said shoulder, and fitting said margins together with the trimmed edge of one abutting the shoulder of the other. 60
60. That improvement in methods of covering heels which consists in covering the rear and sides of a heel with a covering having marginal portions extending forwardly beyond the lateral breast edges of the heel, turning said marginal covering portions inwardly and laying them against the lateral margins of the heel breast, applying a breast covering to cover the uncovered portion of the heel breast and to overlap said inturned margins of the side covering, trimming each lateral margin of the breast covering along a line spaced outwardly from the inner edge of the respective inturned side cover margin and spaced inwardly a substantial distance from the adjacent lateral breast edge to provide a heel breast panel overlapping the inner portions of said inturned side cover margins and framed by the outer portions of said inturned side cover margins, and reducing the edge thickness of the margins of the breast coverings to make them substantially flush with said frame portions. 70
70. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 80
80. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 90
90. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 100
100. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 110
110. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 120
120. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 125
125. That improvement in methods of covering heels which consists in applying to the rear and sides of a heel a side cover having extensions adapted to overlap the lateral margins of the heel breast, rabbeting said cover extensions to receive the lateral edges of a heel breast covering, applying said side cover extensions to the lateral margins of the heel breast, applying to the heel breast a covering wide enough to extend outwardly beyond the rabbeted edge portions of the side cover extensions, trimming the lateral margins of the breast covering along the lines of the outer edges of the rabbeted surfaces on the side cover extensions, and securing the trimmed edges of the breast covering to said rabbeted surfaces. 130

the rear and sides of a heel a side cover having extensions adapted to overlap the lateral margins of the breast face, forming in each of said side cover extensions a shoulder spaced from the adjacent breast corner of the heel and a beveled surface extending from the shoulder to the free edge of the cover extension, securing the beveled edge portions of the cover extensions to the heel breast, applying to the heel breast a covering of a thickness equal to the depth of said shoulders and wide enough to extend outwardly beyond said shoulders, trimming the lateral margins of the breast covering along the lines of said shoulders, fitting the trimmed edges of the breast covering within said shoulders, and securing them to the beveled surfaces of the side cover margins.

18. That improvement in methods of covering heels which consists in applying to the rear and sides of a heel a covering having extensions adapted to overlap the lateral margins of the breast face of the heel, rabbeting said extensions to provide recessed surfaces to be engaged by the lateral margins of a breast covering and shoulders to be engaged by the edges of the breast covering, applying the rabbeted side cover extensions to the heel breast, applying to the breast a covering wide enough to overlie and extend beyond the rabbeted portions of the side cover extensions, trimming the breast covering along the lines of the shoulders in the side cover extensions, and fitting the trimmed margins of the breast covering within the rabbeted portions of the side cover extensions.

19. That improvement in methods of covering heels which consists in applying to the rear and sides of a heel a covering having extensions adapted to overlap the lateral margins of the breast face, forming in each of said cover extensions a depressed surface extending outwardly from the inner edge of the extension and a shoulder spaced inwardly from and parallel to the adjacent lateral edge of the heel breast and applying the side cover extensions to the breast of the heel, applying a breast covering to the heel breast with the lateral margins of the breast covering overlying the side cover extensions and extending outwardly beyond said shoulders, trimming the breast covering to fit between said shoulders while saging the trimming cuts from the lateral edges of the heel breast, and securing the lateral margins of the breast covering in place against the depressed surfaces and shoulders of the side cover margins.

20. That improvement in methods of covering heels which consists in applying to the rear and sides of a heel a covering having extensions adapted to overlap the lateral margins of the breast face, bending each of said cover extensions inwardly at a sharp angle along a line above and parallel to the adjacent lateral edge of the heel breast,

skiving the outer surface of the inwardly bent portion of each side cover extension to provide a beveled surface extending from the inner edge of said inwardly bent portion to a location between the line of bend and the adjacent lateral edge of the heel breast, laying the beveled side cover extension against the heel breast thereby eliminating the bend and causing a shoulder to be formed at the outer margin of the beveled surface, trimming a breast covering to fit the heel breast between said shoulders and applying the trimmed breast covering to the heel breast.

In testimony whereof I have signed my name to this specification.
